(57) **ABSTRACT**

A new *Calibrachoa* plant particularly distinguished by having very large white flowers with yellow centers and a semi-upright and mounding habit, is disclosed.

1 Drawing Sheet

1

Genus and species: *Calibrachoa* sp.
Variety denomination: 'KLECA16314'.

**CROSS-REFERENCE TO RELATED
APPLICATIONS**

This application claims priority to and the benefit of European Community Plant Variety Rights application filed on Mar. 6, 2017, File No. 2017/0698, the entire contents of which are incorporated herein by reference for all purposes.

BACKGROUND OF THE NEW PLANT

The present invention comprises a new and distinct variety of *Calibrachoa*, botanically known as *Calibrachoa* sp., and hereinafter referred to by the variety name 'KLECA16314'. 'KLECA16314' originated from a controlled-cross performed in summer 2012 between two unpatented *Calibrachoa* plants, the proprietary female *Calibrachoa* parent 'CA-2012-0042' and the proprietary male *Calibrachoa* parent 'CA-2011-0378', in Stuttgart, Germany.

The seeds from the cross were sown and plants were grown in a greenhouse for evaluation, where an individual plant designated 'KLECA16314' was selected from the group of plants in May 2013 in Stuttgart, Germany. In May 2013, 'KLECA16314' was first vegetatively propagated by terminal tip cuttings. 'KLECA16314' was found to repro-

2

duce true to type in successive generations of asexual propagation via tissue culture and terminal tip cuttings.

SUMMARY

5 The following are the most outstanding and distinguishing characteristics of this new variety when grown under normal horticultural practices in Stuttgart, Germany.

1. Very large white flowers with yellow centers; and
10 2. A semi-upright and mounding habit.

DESCRIPTION OF THE PHOTOGRAPH

15 This new *Calibrachoa* plant is illustrated by the accompanying photograph which shows the whole plant, including the habit, the foliage, the flowers, and the buds. The photograph is of a 7-week-old plant grown in a pot outdoors in Stuttgart, Germany in April 2015. The colors shown are as true as can be reasonably obtained by conventional photographic procedures.

DESCRIPTION OF THE NEW VARIETY

20 The following detailed descriptions set forth the distinctive characteristics of 'KLECA16314'. The data which define these characteristics were collected from asexual reproductions carried out in Stuttgart, Germany. Data was collected on 20-week-old plants grown in a glass greenhouse

in Stuttgart, Germany. Color references are to The R.H.S. Colour Chart of The Royal Horticultural Society of London (R.H.S.) (2007).

Classification:

Family.—Solanaceae.

Botanical.—*Calibrachoa* sp.

Common.—*Calibrachoa*.

Designation.—‘KLECA16314’.

Parentage:

Female parent.—Proprietary *Calibrachoa* line ‘CA-2012-0042’ (unpatented).

Male parent.—Proprietary *Calibrachoa* line ‘CA-2011-0378’ (unpatented).

Plant:

Life cycle.—Annual.

Habit.—Semi-upright and mounding.

Height (from soil line to top of foliage).—13.0 cm.

Spread.—40.0 cm.

Propagation.—Vegetatively propagated by tip cuttings and tissue culture.

Time to produce a rooted cutting.—3 weeks.

Stems:

Stem color.—RHS 145A.

Pubescence.—Absent.

Diameter.—0.1 cm to 0.25 cm.

Length.—22.0 cm. From soil line to first node: 1.5 cm.

Total length: 22.0 cm.

Internode length.—0.8 cm to 2.0 cm.

Leaves:

Arrangement.—Opposite.

Shape.—Lanceolate.

Apex.—Obtuse.

Base.—Attenuate.

Margin.—Ciliate.

Surface texture.—Smooth.

Surface pubescence.—Absent.

Pubescence color.—Absent.

Venation pattern and color.—Not visible.

Length.—2.0 cm to 3.5 cm.

Width.—0.6 cm to 1.4 cm.

Color.—Upper surface: RHS 137A. Lower surface:

RHS 137B.

Fragrance.—Absent.

Flowers:

Flower type.—Determinate inflorescence with single flowers.

Flowering requirements.—A minimum of light sun is required.

Duration of flowers on the plant.—6 days.

Shape.—Funnel-form.

Fragrance.—Absent.

Flower depth.—2.2 cm.

Flower tube length.—1.8 cm to 2.0 cm.

Flower tube diameter.—1.0 cm.

Flower diameter.—2.6 cm to 3.4 cm.

Pedicel color.—RHS 145A.

Pedicel length.—0.7 cm.

Pedicel diameter.—0.1 cm.

Flower buds:

Surface texture.—Hirtellous.

Length.—1.7 cm to 2.0 cm.

Diameter.—0.4 cm to 0.6 cm.

Shape.—Oblong.

Color.—RHS 2D.

Peduncle:

Length.—1.0 cm to 1.5 cm.

Diameter.—0.1 cm.

Color.—RHS 145A.

Surface texture.—Smooth but with fine hairs.

Anthocyanin color.—Absent.

Petals:

Shape.—Obcordate.

Length.—1.6 cm.

Apex.—Truncate.

Margin.—Entire, with strong undulation.

Base.—Open and fused in the tube.

Pubescence.—Absent.

Lobe length.—1.4 cm to 1.7 cm.

Lobe width.—1.5 cm.

Color.—Lobe color: Upper surface: RHS NN155C with RHS 3B centers. Lower surface: RHS NN155C.

Corolla tube color: Inner surface: RHS 13C. Outer surface: RHS 13D.

Fragrance.—Absent.

Sepals:

Calyx.—Funnel-shaped, salverform.

Shape.—Lanceolate.

Apex.—Acute.

Margin.—Entire.

Length.—1.0 cm to 1.4 cm.

Diameter.—0.2 cm to 0.3 cm.

Color.—Upper surface: RHS 137B. Lower surface: RHS 145A.

Reproductive organs:

Stamen.—Quantity per flower: 5. Anther color: RHS 7A. Filament color: RHS 145C. Filament length: 0.8 cm. Pollen color: RHS 7A. Pollen amount: Medium.

Pistil.—Ovary, placenta arrangement: Ovate. Pistil number per flower: 1. Pistil length: 1.0 cm. Stigma color: RHS 143B. Style length: 0.9 cm. Style color: RHS 150C.

Fruit and seed set: None observed.

COMPARISON WITH PARENTAL LINES AND KNOWN VARIETY

‘KLECA16314’ is distinguished from the female and male parental lines as described in Table 1.

TABLE 1

Characteristic	Comparison with Parental Lines		
	‘KLECA16314’	Female parent ‘CA-2012-0042’	Male Parent ‘CA-2011-0378’
Flower color	White with yellow centers	Red with a yellow star pattern	Pink

‘KLECA16314’ is most similar to the commercial *Calibrachoa* plant named MINIFAMOUS NEO ‘White 12’ (unpatented). Differences between the two varieties are described in Table 2.

TABLE 2

Characteristic	Comparison with Similar Variety	
	‘KLECA16314’	MINIFAMOUS NEO ‘White 12’
Growth habit	Semi-upright	Trailing
Size of center color at transition to corolla tube	Very large	Absent
Color at transition to corolla tube	Yellow	Absent/White

We claim:

1. A new and distinct variety of *Calibrachoa* plant named 'KLECA16314' as illustrated and described herein.
